J. FRAPPY

SEPTIC TANK

Filed Oct. 26, 1927

UNITED STATES PATENT OFFICE.

JOSEPH FRAPPY, OF STIRLING, ONTARIO, CANADA.

SEPTIC TANK.

Application filed October 26, 1927. Serial No. 228,867.

The main objects of this invention are: First, to provide an improved septic tank comprising a plurality of separate containers in which the containers may be easily and effectively installed in assembled relation, at the same time providing proper connecting passages therefor.

Second, to provide an improved septic tank which may be properly installed by inexperienced workmen.

Third, to provide an improved septic tank which is very economical in its parts and at the same time efficient for the purposes intended.

15 Objects relating to details and economies of construction and operation of my invention will appear from the detailed description to follow. The invention is defined and pointed out in the claims.

20 A structure which is a preferred embodiment of my invention is illustrated in the accompanying drawing, forming a part of this application, in which:

Fig. 1 is a fragmentary view of a septic tank embodying the features of my invention partially in section on a line corresponding to line 1—1 of Fig. 2.

Fig. 2 is a detail side elevation partially in vertical central section on a line corresponding to line 2—2 of Figs. 1 and 3.

Fig. 3 is a detail view partially in vertical section on a line corresponding to line 3—3 of Fig. 1.

Fig. 4 is an elevation of one of the baffle passage members employed for the inlet and discharge conduits.

Fig. 5 is a perspective view of one of the passage top members.

In the drawing similar reference characters refer to similar parts throughout the several views.

In the embodiment illustrated, I have shown a pair of containers but it will be understood that the number may be increased where occasion requires, although the structure illustrated is a complete operative unit.

I provide a pair of cylindrical containers, 1, 1 which, when employed in a single unit installation, are duplicates. These containers have flattened side faces 2 which are disposed in opposed abutting relation. These flattened faces have registering openings 3 therein. The containers also have openings 4 in their side walls preferably opposite the openings 3, the openings 4 being in the em-

bodiment illustrated, rectangular as are also the openings 3.

I provide a combined locking or key and passage member 5 preferably oval in cross section and of such dimensions as to fit within the openings 3 constituting a locking or key means for maintaining the containers in proper assembled relation.

The member 5, as illustrated, has grooves 6 in its side and bottom, these grooves being 65 embraced by the edges of the openings 3 and adapted to receive a joint sealing material, as conventionally illustrated at 7. The containers may be further connected and sealed by an outer joint filling 8. 70

The member 5 has a central vertical partition 9 providing vertical passages 10 connected at their tops through the openings 11 in the partition. This forms a return or baffled passage connecting the two containers. 75

I also provide a pair of inlet and discharge conduit baffle members 12 which are of channel cross section and arranged on the inner sides of the containers to coact with 80 the walls thereof and providing vertical passages 13. These members 12 have rectangular outer wall portions 14 which fit within and are secured in the openings 4 of the containers, the portions 14 of the members 12 85 having holes 15 therein to receive the inlet and discharge conduits as 16 and 17.

The tops of the passages 10 of the passage member 5 and of the inlet conduit baffle member 12 are provided with covers or top closures 18, these for convenience in assembling being formed as flat plates of proper dimensions to rest on the tops of the members 5 and 12 and to be retained thereon by cementing. 90

The container covers 19 are in the form of slabs of concrete of suitable form and dimensions, the upper edges of the containers having joint grooves 20 facilitating the effective sealing of the joints. 95

By thus forming and arranging the parts, they may all be formed of concrete without the necessity of excessive weight and they may be easily installed.

Where an installation of a capacity exceeding that of the pair of containers is desired, one or more additional containers having flattened faces on both sides are installed with communicating openings therein, a series of anaerobic bacteria containers 100 110

being thus provided which in effect constitute a single container.

Having thus described my invention, what I claim as new and desire to secure by Letters Patent, is:

1. A septic tank comprising cylindrical containers having flattened side faces with openings therein disposed in opposed abutting relation with their openings registering, said containers also having side openings in their walls opposite said flattened faces, a combined locking and passage member disposed vertically in said registering openings and fitting therein to constitute a locking member for said containers, said passage member having a vertical partition aligned with the abutting walls of said containers and having an opening at the top thereof providing a pair of vertical passages connected at the top and coacting to provide a return passage connection for said containers, inlet and discharge conduit baffle members of channel cross section disposed on the inner sides of said containers to coact with the walls thereof providing vertical inlet and discharge passages, said baffle members having outer wall portions at the tops thereof conformed to and secured within said side openings in said container walls and having openings therein to receive inlet and discharge conduits, closures for the top of the passages of said passage member and of the inlet baffle member, and covers for said containers.
2. A septic tank comprising cylindrical containers having flattened side faces with openings therein disposed in opposed abutting relation with their openings registering, said containers also having side openings in their walls opposite said flattened faces, a combined locking and passage member disposed vertically in said registering openings and fitting therein to constitute a locking member for said containers, said passage member having a vertical partition aligned with the abutting walls of said containers and having an opening at the top thereof providing a pair of vertical passages connected at the top and coacting to provide a return passage connection for said containers, inlet and discharge conduit baffle members of channel cross section disposed on the inner sides of said containers to coact with the walls thereof providing vertical inlet and discharge passages, said baffle members having outer wall portions at the tops thereof conformed to and secured within said side openings in said container walls and having openings therein to receive inlet and discharge conduits, and covers for said containers.
3. A septic tank comprising cylindrical containers having flattened side faces disposed in abutting relation and provided with registering openings, said containers having

outer openings in their walls, a combined key and passage member having vertical passages therein connected at the top disposed vertically in said registering openings of said containers and constituting a locking member therefor, inlet and discharge conduit baffle members of channel cross section disposed on the inner sides of said containers and having outer wall portions conformed to and secured within said outer openings in said container walls, and covers for said containers.

4. A septic tank comprising cylindrical containers having flattened side faces disposed in abutting relation and provided with registering openings, said containers having outer openings in their walls, a passage member having a baffled passage therein disposed in said registering openings, inlet and discharge conduit baffle members of channel cross section disposed on the inner sides of said containers and having outer wall portions adapted to receive conduits secured within said openings in said container walls, and covers for said containers.

5. A septic tank comprising cylindrical containers having flattened side faces with openings therein disposed in opposed abutting relation with their openings registering, and a combined locking and passage member disposed vertically in said registering openings and fitting therein to constitute a locking member for said containers, said passage member having a vertical partition aligned with the abutting walls of said containers and having an opening at the top thereof providing a pair of vertical passages connected at the top and coacting to provide a return passage connection for said containers, said member having joint sealing material receiving grooves therein embraced by the edges of said openings of said containers.

6. A septic tank comprising cylindrical containers having flattened side faces with openings therein disposed in opposed abutting relation with their openings registering, and a combined locking and passage member disposed vertically in said registering openings and fitting therein to constitute a locking member for said containers, said passage member having a vertical partition aligned with the abutting walls of said containers and having an opening at the top thereof providing a pair of vertical passages connected at the top and coacting to provide a return passage connection for said containers.

7. A septic tank comprising cylindrical containers having flattened side faces disposed in abutting relation and provided with registering openings, said containers having outer openings in their walls, and a combined key and passage member having vertical passages therein connected at the top dis-

posed vertically in said registering openings of said containers and constituting a locking member therefor, said member having sealing material grooves in its walls embracing 5 by the edges of said openings.

8. A septic tank comprising cylindrical containers having flattened side faces disposed in abutting relation and provided with registering openings, said containers having 10 outer openings in their walls, and a combined key and passage member having vertical passages therein connected at the top disposed vertically in said registering openings of said containers and constituting a locking 15 member therefor.

9. A septic tank comprising cylindrical containers having flattened side faces disposed in abutting relation and provided with registering openings, said containers 20 having registering openings in their walls, and a passage member having a baffled passage therein disposed in said registering openings.

10. A septic tank comprising containers 25 having side faces disposed in abutting relation and provided with registering openings, and a passage member having a return passage therein disposed in said registering

openings and constituting a locking member for said containers, said member having 30 joint sealing material grooves in its walls embraced by the edges of said openings.

11. A septic tank comprising a container having an opening in its side wall, a baffle member of channel cross section disposed 35 on the inner side of said container to coact with the wall thereof providing a vertical passage, said baffle member having an outer wall portion at the top thereof conformed to and secured within said side opening in 40 said container wall and having an opening therein to receive a conduit, and a closure for the top of said baffle member.

12. A septic tank comprising a container having an opening in its side wall, and a 45 baffle member of channel cross section disposed on the inner side of said container to coact with the wall thereof providing a vertical passage, said baffle member having an outer wall portion at the top thereof conformed to and secured within said side opening in 50 said container wall and having an opening therein to receive a conduit.

In witness whereof I have hereunto set my hand.

JOSEPH FRAPPY.
